UNITED STATES PATENT OFFICE.

HERMAN TIEDEMANN, OF PITTSBURG, PENNSYLVANIA.

RAIL-JOINT.

SPECIFICATION forming part of Letters Patent No. 691,207, dated January 14, 1902.

Application filed October 26, 1901. Serial No. 80,088. (No model.)

To all whom it may concern:

Be it known that I, HERMAN TIEDEMANN, a citizen of the United States of America, residing at Pittsburg, in the county of Allegheny 5 and State of Pennsylvania, have invented certain new and useful Improvements in Rail-Joints, of which the following is a specification, reference being had therein to the accompanying drawings.

10 This invention relates to certain new and useful improvements in rail-joints, and has for its object to construct a device whereby the ends of the rails may be joined together and securely fastened without the aid of bolts 15 and nuts, and, further, aims to construct a neat and effective joint between the two rails.

Briefly described, the invention consists in employing but one fish-plate, which is placed against the outer face of the rails and has an 20 angular lug on each end, which fits into openings provided therefor in the webs of the rails. This fish-plate or locking-bar is engaged in an opening in one rail, and the other rail is 25 engaged with the fish-plate or locking-bar by placing the second rail in angular relation to the first rail and swinging it around into alignment therewith.

In describing the invention in detail reference is had to the accompanying drawings, 30 forming a part of this specification, wherein like numerals of reference indicate corresponding parts throughout the several views, and in which—

Figure 1 is a detail perspective view of a 35 part of two rails, showing my improved joint in position. Fig. 2 is a top plan view thereof, partly in horizontal section, the better to show the joint and showing in dotted lines how the one rail is swung around on its pivot to engage and disengage the same from the fish-plate or locking-bar. Fig. 3 is a detail perspective view of the fish-plate or locking-bar.

To put my invention into practice, I provide the rails 1 and 2 with openings 3 in the 40 web thereof, and I preferably cut the meeting ends 4 of these rails at an angle of about forty-five degrees to the tread, so that the said ends will match neatly together. The rails are held in longitudinal alinement by means

of the locking-bar or fish-plate 5 having a 50 base portion 6 to engage the base of the rail. This locking-bar or fish-plate is adapted to be engaged with the outer face of the rails and is provided on each end with an angular lug 7, the height of this lug being less than the 55 height of the body portion 5 of the locking-bar, so as to permit their ready engagement or disengagement with the slots or openings 3 in the webs of the rails.

To apply the joint, the locking-bar 5 has the 60 lug 7 on one end thereof placed into engagement with the rail 1, this engagement being effected by inserting the lug of the bar with the latter placed at right angles to the rail, and then turned into engagement with the 65 rail in the position shown in Figs. 1 and 2. The rail 2 is then engaged with the locking-bar or fish-plate by placing the rail at right angles to the rail 1, engaging the lug 7 on the other end of the bar 5 in the opening 3 in the 70 rail, and swinging the said rail 2 around into alinement with the rail 1, as shown in Fig. 2 of the drawings. The rails are held to the ties by spikes, as in the ordinary manner. As the locking-bar or fish-plate is applied to the 75 outer face of the rails, all pressure is against the fish-plate and the spreading of the rails is effectually prevented.

While the accompanying illustrations show the practical embodiment of my invention, 80 yet in the practice thereof it will be observed that various changes may be made in the details of construction without departing from the general spirit of my invention.

Having fully described my invention, what 85 I claim as new, and desire to secure by Letters Patent, is—

1. A rail-joint which comprises a base-plate carrying a fish-plate engaging one side of the rail-web and an angular lug on each end of 90 said fish-plate for engagement with the opposite side of the web, substantially as described.

2. A rail-joint comprising an integral fish-plate each end of which has an angular lug, said fish-plate engaging one side of the said 95 rail-web and the said angular lugs each engaging the opposite side, substantially as described.

3. A rail-joint which comprises a single fish-plate carrying an angular lug on each end thereof, in combination with rails having openings formed therein for the reception of said lugs engaging one side of the rail-web, the fish-plate engaging the opposite side thereof, the rails having their ends cut at an angle whereby one rail may be swung at an

angle to the other and the rails disengaged, substantially as described.

In testimony whereof I affix my signature in the presence of two witnesses.

HERMAN TIEDEMANN.
